UNITED STATES PATENT OFFICE.

BENAGE S. JOSSELYN, OF DENVER, COLORADO.

DESIGN FOR A SPOON.

SPECIFICATION forming part of Design No. 21,519, dated May 10, 1892.

Application filed March 28, 1892. Serial No. 426,826. Term of patent 3½ years.

To all whom it may concern:

Be it known that I, BENAGE STOCKWELL JOSSELYN, a citizen of the United States, residing at Denver, in the county of Arapahoe and State of Colorado, have invented and produced a new and original Design for Spoons, of which the following is a specification, reference being had to the accompanying drawing, showing the whole thereof.

10 The figure on the drawing represents a front or face view of the spoon, this one view alone being deemed necessary to fully illustrate my design.

15 The leading feature of my design consists in raised-work surface, the outlines of which when viewed in elevation, as in drawing, will represent various distinct figures.

A is the head of the spoon, which represents two Arabs mounted on two camels, with

view of three pyramids in the background, 20 all in raised work.

B is the center of handle and represents a Turkish cap or fez, on the face being shown a cimeter, suspended from which is a crescent, and suspended from center of the crescent is 25 a five-pointed star, all in raised work.

C is the bowl of the spoon, upon which is placed a Turkish cimeter, suspended from which is a crescent, and suspended from the center of the crescent is a five-pointed star. 30

What I claim is—

The design for a spoon, herein shown and described.

BENAGE S. JOSSELYN.
